Des. 215,670
Patented Oct. 21, 1969

215,670

HAND-HELD PAINT SCRAPER OR SIMILAR ARTICLE

Meyer M. Katz, Melrose Park, Philadelphia, Pa., assignor
to Crystal Metal Products Co., Inc., Philadelphia, Pa.,
a corporation of Pennsylvania

Continuation-in-part of design application Ser. No. 6,105,
Mar. 7, 1967. This application Apr. 25, 1968, Ser. No.
11,615

Term of patent 14 years

Int. Cl. D7—06

U.S. Cl. D49—26

FIG.1

FIG.5

FIG.2

FIG.3

FIG.4

FIGURE 1 is a front perspective view of a hand-held paint scraper or similar article showing my novel design;

FIGURE 2 is a side elevational view thereof;

FIGURE 3 is a top plan view thereof;

FIGURE 4 is a bottom plan view thereof;

FIGURE 5 is a front elevational view thereof; and

FIGURE 6 is a rear elevational view thereof.

This is a continuation-in-part of design application Ser. No. 6,105, filed Mar. 7, 1967, and now abandoned.

I claim:

The ornamental design for a hand-held paint scraper or similar article, substantially as shown.
